UNITED STATES PATENT OFFICE.

ERNEST C. PRATT, OF MINNEAPOLIS, MINNESOTA.

METHOD OF MINING COAL.

Application filed March 20, 1926. Serial No. 96,221.

My invention relates to methods of mining coal and has for its object to provide a method by which coal may be expeditiously and economically removed from the 5 face of the room in which the mining occurs and loaded on pit cars which may be moved into the entries of the mine and hauled to the hoists in the mine shaft.

An object of the invention resides in providing a method of mining coal in which the room where the mining is taking place is equipped with two tracks having pit cars thereon, also with a coal loader and a transfer truck adapted to move cars bodily, which 10 method consists of loosening the coal at the face, in scooping up the coal and depositing it upon the loader, of moving a pit car bodily from one track to said loader, discharging the coal from the loader upon the 15 pit car moving the pit car bodily back to said second track and placing said pit car thereon.

With the foregoing and other objects in view, which will appear in the following 20 description, the invention resides in the novel combination and arrangement of parts and in the details of construction hereinafter described and claimed.

The drawing is a plan sectional view of a 25 room in a mine illustrating apparatus by means of which the method may be carried out.

In the mining of coal by the usual methods, considerable time is lost where a 30 single track is employed, while a loaded pit car is being moved from the room in which the mining is taking place to the mine entry and an empty brought back. During such movement of a pit car the loader usually remains idle a part of the time awaiting the 35 return of the empty car. In my improved method of mining coal, the trip cars are moved practically continuously from the incoming track to the loader and back again to the outgoing track so that loss of time 40 is greatly reduced, allowing the loader to operate substantially without interruption.

For the purpose of illustrating the application of the invention, I have disclosed 45 a portion of a coal mine of the room and pillar type, though it will readily become apparent that my improved method of mining may be used in other kinds and types of mines. In the drawing, a mine room has been illustrated, which is formed with a neck 50 leading into the entry or other passage-

way of the mine not shown in the drawing. The room A is elongated in form, widening out to a maximum width immediately beyond the neck 10 and remaining substantially the same width throughout its length. The coal is loosened from the face of the room A, indicated at 11, so that as the mining progresses the room A is lengthened until it reaches the end of its course or becomes connected with other rooms of the mine. All of the coal is taken out of a room A through the neck 10 and my invention is particularly concerned with the expeditious handling of the coal in said 60 room and the removal of the coal therefrom.

Within the entries of the mine are laid tracks which lead up to the hoisting apparatus in the mine shaft, not shown in the 65 drawing. A spur track 12 connected with one of these tracks in the entries passes along the neck 10, where it divides forming two branches 13 and 14 connected by a suitable switch 15. The track 13 is used for ingress into the room A, while the track 14 is used for egress. Upon the track 13 are stored empty cars 16 while loaded cars 17 are placed upon the track 14.

In addition to the tracks and cars the 70 room A of the mine is equipped with a loader B and a transfer truck C which function in a manner presently to be described. The loader B may be of the type illustrated in Letters Patent numbered 1,508,856 75 and 1,508,857 both issued to me September 16, 1924, which type of loader includes a scoop 18, adapted to scoop up the coal loosened in a fall and raise it and deposit it upon a hopper equipped with a discharge 80 conveyor 19. This hopper is sufficiently raised above the ground so that the coal placed thereon may be discharged over the end of the same and into any suitable receiver placed beneath it. The whole structure is mounted on a framework 20 carried by two caterpillar units 21 and 22 propelled and manipulated to cause the loader to operate in any position along the face 11.

The transfer truck C may be of the type 85 disclosed in my accompanying application for patent, Serial Number 96,224, filed March 20, 1926, which truck consists of an underslung framework 23 supported on two caterpillar units 24 and 25, said framework 90 carrying two rails 26 and 27 adapted to register with the rails of track 16 or 17 when

the truck is brought up to either of these tracks. The truck further is provided with mechanism by means of which cars may be drawn from the tracks and upon the rails 5 26 and 27 or removed from said rails and placed upon the track.

The various steps in my improved method of mining coal are as follows. Empty cars 16 are first run in upon the branch track 13 10 to the end of the same. Truck C is next brought up to the end of track 13 so as to cause the rails of said track to register with the rails 26 and 27 of said track. In this position the first of the incoming cars 16 15 on track 13 is uncoupled and by means of the mechanism previously alluded to, is drawn upon said rails, said car being indicated at 28 in the drawing. By propelling truck C, car 28 is moved bodily to any location 20 within the room A at which the loader B is operating. When said loader is at the end of the face 11 as illustrated, truck C is first backed up along the course indicated at 29 and then moved forwardly along the 25 course 31 until the car 28 becomes positioned so as to receive the coal discharged from the conveyor 19 of loader B. As the coal is scooped up by scoop 18 and deposited upon the conveyor 19, said conveyor is advanced step by step until the same is loaded 30 with fuel throughout its length. The coal is then discharged into the pit car 28 carried by truck C and the loading of conveyor 19 again resumed. While the loading of this 35 conveyor occurs truck C is retraced along its path of travel indicated at 31 and then advanced along a course 30 until it takes the position shown in dotted lines, with the rails 26 and 27 thereof registering with the 40 ends of the rails of track 14. In this position pit car 28, which is now loaded may be placed upon track 14 and coupled to the other loaded cars 17. After car 28 is removed from truck C, said truck again may retrace its course 45 of travel over routes 30 and 29, pick up another empty car 16, carry it over to the loader B to be loaded, from its then replenished hopper, and, finally, bring said loaded car back to track 14. In this manner a cycle of operations occur where the loader B operates practically continuously 50 as long as sufficient empty cars are available. When the last car is being loaded, the locomotive brings in a new trip of empties 55 spotting them on track 13 and hauls away the loaded trip on track 14, so that very little time need be lost while the loaded cars are being hauled away and the empties brought back again.

60 Inasmuch as only one loader may be advantageously used in each room of the mine, it readily follows that the efficiency of removing the coal depends upon how steadily the loader operates. My improved method 65 of mining coal permits the loader to be at

the face of a room at all times and allows the loaded cars to be removed and empty cars brought back just as fast as the cars are loaded so that the loader is in operation practically at all times. Further, my improved method is highly advantageous in that the requirements at each of the various rooms for the attendance of a mine locomotive and its trainmen are greatly minimized, and this for the reason that a locomotive is 70 permitted to handle a train of cars at each trip thereof as opposed to the handling of a single pit car under the usual methods. The locomotive requirements for a given room being less under my improved method, it 75 follows that a mine may be expeditiously operated with reduced locomotive equipment and under reduced labor costs for trainmen.

Changes in the form of the apparatus employed and in the steps of my improved method of mining coal may be made without departing from the spirit of the invention within the scope of the following claims.

Having described my invention, what I claim as new and desire to protect by Letters Patent is:

1. The method of mining coal which consists in accumulating coal in a loader at the face of a room having a number of tracks, in removing an empty pit car from one track and moving it to a position remote from said tracks and adjacent said loader, discharging the coal from said loader directly into said pit car, and of moving such loaded 100 pit car to a second track.

2. The method of mining coal which consists in accumulating coal in a loader at the face of a room in which mining is being carried on, propelling a transfer truck up to the end of a track having empty pit cars stored thereon, running the first of said empty pit cars upon said transfer truck so as to be carried bodily thereon, propelling said truck and pit car to a position adjacent 110 said loader, discharging the coal from said loader directly into said pit car, propelling said transfer truck and loaded pit car to the end of a second track and removing said loaded pit car from said transfer truck and 115 placing it upon said second track.

3. The method of mining coal consisting in the employment within a room of a mine of two tracks ending in said room, pit cars having ingress to the room on one track 120 and egress therefrom on the second track, a self dumping loader for scooping up and accumulating loads of coal, and a pit car transfer truck, said truck being employed to carry an empty pit car from said first track 125 to said loader and to carry said pit car loaded from said loader to said second track.

4. The method of mining coal consisting in the employment within a room of a mine of two tracks ending in said room, pit cars 130

having ingress to the room on one track and egress therefrom on the second track, and a pit car transfer truck, said truck being employed to carry empty pit cars 5 from said first track to a remote locality for loading and to carry said pit cars loaded to said second track.

5. The method of mining coal in a room in a coal mine having two tracks, one for 10 ingress and another for egress and pit cars for said tracks, said room being further equipped with a loader and a transfer truck, which method consists in accumulating coal at the face of the room upon said loader, 15 moving empty pit cars bodily by said transfer truck from said track for ingress into the room to said loader, discharging the coal from said loader directly into said pit cars, moving said loaded pit cars bodily by

said transfer truck to said track for egress 20 from said mine room, and in removing said loaded trip car from said truck and depositing it upon said last named track.

6. The method of mining coal which consists in accumulating coal in a loader at the 25 face of a room in which the mining is carried on, moving an empty pit car from one track to a temporary support, moving said support and pit car to a position adjacent said loader, discharging coal from said 30 loader directly into said pit car, moving said support and loaded pit car to a second track and moving said loaded pit car from said support to said second track.

In testimony whereof, I have signed my 35 name to this specification.

ERNEST C. PRATT.
